BALE TIE OPENER

Filed May 10, 1924

UNITED STATES PATENT OFFICE.

ARISTIDE FREDERICK RENAUD, OF HOUSTON, TEXAS, ASSIGNOR TO HOUSTON COMPRESS COMPANY, INC., OF HOUSTON, TEXAS, A CORPORATION OF TEXAS.

BALE-TIE OPENER.

Application filed May 10, 1924. Serial No. 712,320.

This invention relates to a tool for breaking buckles and the like, and is more particularly designed for breaking the buckles of cotton bale ties. It will be here shown how 5 put to such use. It will be understood, however, that it is not limited to this specific operation, but may be adapted to the breaking of other and different fastenings.

In the baling of cotton, it is customary to 10 use ties of relatively thin metal, which ties, at their meeting ends, are bent upon themselves to form buckle engaging loops. In the baling operation, these loops are engaged with the ordinary buckle of commerce, which 15 is substantially rectangular and fashioned somewhat in the form of a letter C and the shape of a safety pin, the tie loops being passed into the eye of the buckle through a passage in a side link and securely held there- 20 by when the parts are brought to proper relation in the baling operation.

When the bale is opened, it is necessary either to cut the tie, or to break the buckle. The breaking of the buckle is preferable, for 25 the reason that its cost is small, compared with that of the tie, and preferably the tie should be preserved for repeated use. It is customary to cut the tie with an ax, or open the buckle by twisting, which, in the 30 first case, causes a loss of about fourteen (14) inches in the length of the tie, and in the second so twists and distorts the tie that the ends have to be cut off, and pieces riveted on to same before it can be restored to a usable 35 length.

It is the object of the present invention to provide a tool which, in the hands of even an unskilled workman, will very quickly and surely break the buckles, while, at the same 40 time, the bale ties are so held that they are not subjected to any distortion, but are maintained in their original smooth, untwisted condition, ready for further use.

In the drawings herewith, I have illus- 45 trated a tool embodying my invention, which tool may, of course, be varied, so far as mechanical changes and design are concerned, and this disclosure is to be taken as merely illustrative and not restrictive of my inven- 50 tion.

In the drawings:—

Fig. 1 is a view in side elevation of a tool embodying my invention, part of the handle

portions being broken away because of restricted space. 55

Fig. 2 is a view in side elevation, on an enlarged scale, of the head of the tool, parts being broken away for clearness of illustration.

Fig. 3 is a view in plan of the head shown 60 in Fig. 2, the bale tie and the buckle being shown in dotted lines.

Fig. 4 is an end view looking from the right, Figure 3, showing the end of the tool and illustrating the buckle and bale tie in 65 full lines.

Referring to the drawings by numbers, like numbers indicating like parts in the several views, and referring first to Figure 1, the tool is made up of the handle members 10 of any 70 suitable design and construction pivotally connected at 11, so as to be movable relative to each other. The handle members are provided with grips 12 of any suitable shape or design, and the angular relation of these 75 grips to the handles may be varied, as desired. I have here shown in full lines a straight position, and one angular position in dotted lines.

Each of the handles 10 is provided, at its 80 forward end, in front of the fulcrum pivot 11, with lever projections pivotally connected at 13 with the breaker members in the form of levers 14, which breaker members are pivoted at 15 in a supporting head formed of carrier plates 16. The members 14 terminate at their forward ends in the reduced breaker points 17, and they are preferably geared together at 18 (see Fig. 2) in order to insure 85 uniform and symmetrical lever movements 90 when the members 14 are rocked by the handles 10.

From the foregoing, it will be seen that when the handles 10 are in closed position, as shown in Figure 1, the members 14 will be 95 in the position shown in Figures 1 and 2, ready to be inserted in the eye of the buckle, and that upon spreading or opening the handles 10, the members 14 will be brought together at their inner ends, while the buckle 100 breaking points 17 will be spread. The leverage is such that a very considerable force is exerted as the buckle breaking points 17 separate, the leverages being so worked out that the force generated is sufficient to break the 105 buckle readily.

Figs. 3 and 4 show the tool in position with respect to the bale tie and the buckle 19. It will be seen that the points 17 are engaged with the eye of the buckle ready for the breaking spread. In order to hold the ends of the tie 20 in normal position and prevent their being twisted or distorted, I provide the tie engaging projections 21, which are preferably integral extensions of the lever carrying plates, these projections 21 being offset so as to span the buckle, and having, in their ends, recesses designed to straddle the bale tie on either side of the buckle 19, and, as the tool is thrust downward for engagement, hold 10 the bale tie ends flat and in normal position. When thus engaged, danger of distorting the bale tie is eliminated, for the breaking of the buckle is effected by the straight line movement of the spreading buckle breaking points 20 17, and the breaking line of the buckle is ordinarily through the back limb substantially opposite the loop receiving passage 22 to the eye of the buckle in the other limb. Any tendency to twist the bale tie loops is counteracted by the firm grip which the recessed bale tie engaging projections 21 exert upon the bale tie, and which holds them in flat normal position.

Not only does the tool readily break these 30 buckles and release the tie, but by giving it a slight angular movement or twist after breaking the buckle, the parts of the buckle, if not completely disengaged, may be pulled out of and withdrawn from the bale tie loops.

35 By the use of this tool, bales may be opened very rapidly, and without undue exertion, and what is particularly to be desired, without any destruction or distortion of the bale tie.

40 The tool may, of course, be made in any suitable size, and such changes in its make-up may be made and mechanical expedients other than those here shown adopted as are within the skill of the mechanic and designer, without departing from the range of 45 my invention.

I claim:—

1. In a tool of the class described, the combination of a supporting head formed of 50 spaced carrier plates; a plurality of breaker levers pivotally mounted between said plates and having breaker points at their forward ends adapted to be inserted in an orifice in the thing to be broken; gear sections interconnecting said levers to insure uniform and 55 symmetrical lever movements; means on said carrier plates to engage the work on each side of the breaker points and hold it in normal position during the breaking operation, and 60 pivotally connected handles pivotally engaged with the rear ends of said levers to rock said levers on their pivots, separate the breaker points, and exert a breaking strain.

2. In a tool for breaking bale tie buckles, 65 the combination of a supporting head formed

of spaced carrier plates; a plurality of breaker levers pivotally mounted between said plates and having breaker points at their forward ends adapted to be inserted in the eye of the buckle to be broken; interengaging gear sections on the inner adjacent edges of 70 said levers to insure uniform and symmetrical lever movements; means to engage the bale tie on each side of the buckle and hold it in normal position during the breaking operation; and pivotally connected handles pivotally engaged with the rear ends of 75 said levers to rock said levers on their pivots, separate the breaker points, and exert a breaking strain.

3. In a tool for breaking bale tie buckles, the combination of a supporting head formed of spaced carrier plates; a plurality of breaker levers pivotally mounted between said plates and having breaker points at their forward ends adapted to be inserted in the eye of the buckle to be broken; interengaging gear sections on the adjacent edges of 80 said levers to insure uniform and symmetrical lever movements; means projecting forwardly from said carrier plates to engage the bale tie on each side of the buckle and hold it in normal position during the breaking operation; and pivotally connected handles pivotally engaged with the rear ends of 85 said levers to rock said levers on their pivots, separate the breaker points, and exert a breaking strain.

4. In a tool for breaking bale tie buckles, the combination of a supporting head formed of spaced carrier plates, a plurality of breaker levers pivotally mounted between said plates and having breaker points at their forward ends adapted to be inserted in the eye of the buckle to be broken; interengaging gear sections on the inner adjacent edges of 90 said levers to insure uniform and symmetrical lever movements; integral projections on said carrier plates to engage the bale tie on each side of the buckle and hold it in normal position during the breaking operation; and pivotally connected handles pivotally engaged with the rear ends of 95 said levers to rock said levers on their pivots, separate the breaker points, and exert a breaking strain.

5. In a tool for breaking bale tie buckles, the combination of a supporting head formed of spaced carrier plates; a plurality of breaker levers pivotally mounted between said plates and having breaker points at their forward ends adapted to be inserted in the eye of the buckle to be broken; interengaging gear sections on the inner adjacent edges of 100 said levers to insure uniform and symmetrical lever movements; integral offset projections on said carrier plates to engage the bale tie on each side of the buckle and hold it in normal position during the breaking operation; and pivotally connected handles pivotally engaged with the rear ends 105 of 110

of said levers to rock said levers on their pivots, separate the breaker points, and exert a breaking strain.

6. In a tool for breaking bale tie buckles, the combination of a supporting head formed of spaced carrier plates; a plurality of breaker levers pivotally mounted between said plates and having breaker points at their forward ends adapted to be inserted in the eye 10 of the buckle to be broken; interengaging gear sections on the adjacent edges of said levers to insure uniform and symmetrical lever movements; integral offset projections on said carrier plates having recesses in their 15 forward ends to engage the bale tie on each side of the buckle and hold it in normal position during the breaking operation; and pivotally connected handles pivotally engaged with the rear ends of said levers to rock said 20 levers on their pivots, separate the breaker points, and exert a breaking strain.

7. In a tool for breaking bale tie buckles, the combination of a supporting head formed of spaced carrier plates; the forward ends of 25 which are offset and provided with bale tie engaging recesses; a plurality of breaker levers pivotally mounted between said carrier plates and having breaker points at their forward ends lying between the offset recessed forward ends of the carrier plates and 30 adapted to engage the eye of the buckle to be broken; interengaging gear sections on the inner adjacent edges of said levers to insure uniform and symmetrical lever movements; 35 and a pair of lever actuating handles pivotally connected and having projecting forward ends pivotally engaged with the rear ends of

said levers to rock said levers on their pivots, separate the breaker points, and exert a breaking strain on the buckle. 40

8. In a tool for breaking bale tie buckles, the combination of a supporting head; levers mounted on said head and having buckle engaging breaker points at their forward ends; projections on said head to engage a bale tie 45 on either side of the buckle and hold it in normal position during the breaking operation; a pair of pivotally connected handles, and projections at the forward ends of said handles pivotally connected to the rear ends of 50 said levers to rock said levers on their pivots, separate the breaker points, and exert a breaking strain on the buckle.

9. In a tool of the class described, the combination of a supporting head, pivotally mounted interconnected breaker members mounted in said head, handles pivotally connected to each other and to said breaker members, said head comprising carrier plates extending longitudinally of the breaker members and substantially enclosing them, and means on the said plates for engaging a bale strap, the said breaker members at their free ends projecting beyond the said means whereby they may engage a bale buckle with the 65 said means engaging the bale strap, slight operation of the handles producing the necessary leverage upon the breaker members to separate the buckle while the said means sustains said breaker members as well as the bale 70 strap.

In testimony whereof I have hereunto set my hand.

ARISTIDE FREDERICK RENAUD.
